James Wager of Troy N.Y.
Letters Patent. No. 277. Dated April 2. 1850.

The Schedule referred to in these Letters Patent and making part of the same.

To all to whom these presents shall come:

Be it Known that I. James Wager of Troy in the County of Rensselaer and State of New York have invented or produced a certain new design for stove plates and that the following is a full and clear description thereof reference being had to the accompanying drawings making part of this specification in which Fig 1. is a section of the bottom of base plate of the stove. Fig 2 is a horizontal section through one of the sides. Fig 3. is a section of side plate and top of stove. Fig. 4. is a view of the front end with door.

This design is intended for the ordinary six plate Stove, but is applicable to other kinds of stoves.

The front part of the base plate Fig. 1. has a double raised plain moulding all around the hearth and a single plain moulding quite around the edge of that portion under the body of the stove.

The plate covering the ash pit has a rotary ornamental register or damper.

The side plate a section of which is shown in Fig. 3. has two panels the centre of each being ornamented with a spread eagle standing up on a shield with a cornucopia of fruit and flowers on each side and over which is a scroll with stars and the motto "Vt plus ultra" the top of side plate has a heavy O.S. moulding and under this and at each end and bottom there is a heavy combination of mouldings and with which are two small waved mouldings.

The edge of the top plate as shown in Figs. 3+4 has also a combination of heavy O.S. oval O and cove mouldings. Fig 4 represents the front of stove with mouldings corresponding with the side plates and the panel in centre is ornamented with the Goddess of Liberty.

I claim as my Invention or production

Des. 344

the above described combination of mouldings and illustrated ornamental figures for six plate stoves and desire to secure the same by Letters Patent. —

Witnesses.

John H. Churn
D. F. Wells.

James Wager.
